UNITED STATES PATENT OFFICE.

GEORG JAHN, OF ARNSWALDE, GERMANY.

CENTRIFUGAL MACHINE FOR SEPARATING SOLID SUBSTANCES FROM LIQUIDS.

1,124,907.

Specification of Letters Patent. Patented Jan. 12, 1915.

Application filed April 23, 1914. Serial No. 833,972.

To all whom it may concern:

Be it known that I, GEORG JAHN, civil engineer, a subject of the German Emperor, and resident of Arnswalde, in the Kingdom of Prussia, Germany, Bahnhofstrasse 12, have invented new and useful Improvements in or Relating to Centrifugal Machines for Separating Solid Substances from Liquids, of which the following is a specification.

10 This invention relates to a centrifugal machine of the known kind in which the material, such as for instance clay-slime, starch-milk or the like, is introduced into a quickly rotating drum, the solid particles being projected by the action of centrifugal force, toward those portions of the drum where the speed is the greatest, and settling at the said portions.

In the apparatus hitherto known, the 20 solid substances are conveyed from the zone of the greatest speed through pipes which lead back through the liquid. In that way, the greater part of the drum is not utilized for the development of forces producing 25 separation. But the chief point is that the said pipes exercise a stirring action on the zones of different density formed in the drum.

According to this invention, the pipes 30 through which the solid substances are discharged, are carried direct from the settling point outward, without passing through a liquid zone. In that way, the whole free space of the drum, available from the outer 35 circumference to the overflow, is utilized for separation, and at the same time any stirring of the liquid contained in the drum is completely avoided. Moreover, the liquid masses carried away by the transport or 40 conveyer device, are brought back again at a point where the liquid is the thickest, so that they do not cause any disturbance of the layers of liquid.

A machine of the new kind is illustrated 45 in the accompanying drawing in which—

Figure 1 is a vertical section. Fig. 2 shows a portion of a slightly modified construction, and Fig. 3 shows in section another construction according to this invention.

On the rotating spindle A suitably supported in the machine frame, is secured the centrifugal drum B.

50 The drum B is provided at its outer settling zone, or near the same, at C, with conveyer pipes D for the heavier solid mate-

rials. The conveyer pipes D rotate with the drum, as they are secured to the latter.

In the conveyer pipes are arranged worms E which are separately driven from the center of the spindle by means of wheel gear F or chain gear etc. These driving parts F participate in the rotation of the centrifugal drum, and have also a separate speed, so that the worms E are rotated in the conveyer pipes in order to bring about movement of the material. Some other mechanical conveyer devices, such as elevators etc., could also be used in place of the worms E and mechanical conveying could also be replaced by suction or pressure action, conveyer pipes D engaging with the outermost settling pipe, or near the same, at C, being utilized for the purpose.

The liquids separated escape at G around the whole circumference of the drum. The liquids to be separated are introduced into the drum B from the inside, for instance at H, to the level a—b. The conveyer pipes are of such construction that hollow branches J which connect the conveyer pipes D to the drum B, enable any liquid carried away into the conveyer pipes D to flow back into the drum B to the liquid level a—b. The heavier solid materials are accordingly still further deprived of the liquid by means of the branches J.

In order to enable the worms E or other mechanical conveyer devices to be stopped and started again when the drum is rotating at full speed, the driving pulley K is provided with a loose pulley L, or in place of the loose pulley L, between the driving pulley K and the spindle M is inserted for instance at M, an easily operated coupling or clutch.

The whole centrifugal drum is driven by a pulley O mounted on the spindle A or connected directly to a motor. In place of the clutch or of the driving device, an adjustable brake device could also be arranged on the spindle. The centrifugal machine can be made vertical or horizontal.

The working of the machine is as follows: The centrifugal drum B is driven by means of the pulley O or in some other manner. As the conveyer pipes D rotate with the same, and also the driving mechanism F, the driving pulley K will be driven with the same speed as the centrifugal drum B. In order to give the conveyer worms E, or other conveyer mechanisms, a conveying

movement in the conveyer pipes D, the driving pulley K is rotated. If the worms D or other conveyer devices are temporarily not to make any conveying movement, the 5 rotation of the pulley K is stopped, for instance by moving a belt from the pulley K to the loose pulley L, or by disconnecting an easily operated clutch arranged at N. In place of such a clutch, could also be arranged 10 a simple brake pulley which can then be braked by a suitable brake. It will be readily understood that in this construction if the brake is released, the transport devices F must stop, but that as soon as a 15 braking effort is exercised, the transport devices must rotate, according to the strength of the braking effort, with a speed increasing in proportion to the action of the brakes. The liquids with the heavy solid materials 20 pass for instance at H into the drum B, and a liquid level a—b is formed. The heavier particles settle in the outermost settling zone, at C, the liquids escape at G from the drum B around the whole circumference. 25 The solid particles are conveyed at C through the conveyer pipes D either by means of worms or other mechanical conveying devices or by suction or pressure devices, and escape from the conveyer pipes at 30 P and are projected outward. Any liquids carried away, can return to the drum through the hollow branches J. Owing to the latter, the solid materials are still further deprived of the liquid. The whole process 35 of separation and conveying can take place in a continuous manner.

Fig. 2 shows on a reduced scale another construction of the device in which the conveyer worm is omitted. The carrying away 40 of the solid materials from the pipes D takes place through pipes R by means of which water under pressure or compressed air or steam is introduced into the pipes D. The same effect could also be obtained by 45 connecting the end of the pipe D to a chamber, and connecting the latter in a suitable manner to a vacuum. The end of the pipe R which conveys pressure medium into the pipe D, is preferably made in the shape of a 50 nozzle.

In the construction shown in Fig. 3, the liquid pressure is exclusively used in the drum for the purpose of carrying the solid materials out of the drum. In many cases, 55 more particularly where it is not of importance to get the materials from the centrifugal drum as dry as possible, the centrifugal pressure in the drum is sufficient to force the heavier materials from the drum 60 on the principle of communicating pipes.

The pipes D no longer have any conveying device, it is true that a combination of these adjustable pipes with mechanical conveying devices could be used, but their free 65 end is provided with an adjustable tele-

scopic pipe T. The latter can be radially moved inward and outward on the corresponding pipe D, so that the pipes D can be so to say shortened or lengthened by means of the telescopic pipes T.

According as the liquid to be separated, 70 contains more or less solid materials, and according to the specific gravity of the liquid to be separated being different from the specific gravity of the solid materials, 75 the pipes must be lengthened or shortened. If for instance the pipe T is pulled out to such an extent that the outlet openings are situated on the same cylindrical surface as the level of the liquid in the centrifugal 80 drum, then nothing will be able to issue from the end of the pipes. If however the pipes are shortened, so that their openings 85 are situated on a cylindrical surface of a larger diameter than that corresponding to the liquid level formed by the liquid in the drum, the liquid must issue from the pipes T. As however the other end of the pipes in the drum is lying exactly in that portion 90 in which the separation took place, only solid materials will be driven out through the pipes, as they separate.

By correctly adjusting the pipes T, it is possible to carry out the whole of the solid materials mixed with only more or less 95 liquid. The latter can be removed in any desired manner and if desired carried back.

It is advisable to be able to move all the telescopic pipes T simultaneously, and even during the working, in order to reach the 100 exact position which gives the most favorable removal of the solid materials. To this end, the telescopic pipes T are connected by suitable rods U to a sleeve V adjustable on the spindle A. The sleeve V is provided 105 with a circular groove with which engages a collar v. This collar is connected to the spindle W, and the latter can be moved in the frame of the machine by means of a hand wheel or spindle.

It will be readily understood that, by correctly using the hand wheel X, the telescopic pipes T can be radially moved.

Having now particularly described and ascertained the nature of my said invention 115 and in what manner the same is to be performed, I declare that what I claim is:—

1. A centrifugal separator of the character described comprising a rotary drum, 120 open at one side and closed by a diaphragm at the opposite side, with openings in said diaphragm near the periphery thereof, means for feeding the liquid into the open side of said drum, a series of conduits inclined outwardly from said drum and inwardly toward the rotary axis thereof, a series of telescopic outlet pipes carried by said conduits, and means for simultaneously moving said outlet pipes while said drum is in rotation, substantially as described. 125 130

2. A centrifugal separator of the character described comprising a rotary drum, open at one side and closed by a diaphragm at the opposite side, with openings in said diaphragm near the periphery thereof, means for feeding the liquid into the open side of said drum, and a series of conduits connected to said openings in the diaphragm for conveying the exterior portions of the separating mass away from said drum, said conduits being inclined outwardly away from said drum, and inwardly toward the axis about which said drum rotates, substantially as described. 5
3. A centrifugal separator of the character described comprising a rotary drum, open at one side and closed by a diaphragm at the opposite side, with openings in said diaphragm near the periphery thereof, means for feeding the liquid into the open side of said drum, and a series of conduits connected to said openings in the diaphragm for conveying the exterior portions of the separating mass away from said drum, with 10 means for positively controlling the flow of fluid through said conduits, substantially as described. 15
4. A centrifugal separator of the character described comprising a rotary drum, open at one side and closed by a diaphragm at the opposite side, with openings in said diaphragm near the periphery thereof, means for feeding the liquid into the open side of said drum, and a series of conduits 20 connected to said openings in the diaphragm for conveying the exterior portions of the separating mass away from said drum, with means for positively controlling the flow of fluid through said conduits, substantially as described. 25
5. A centrifugal separator of the character described comprising a rotary drum in the form of a hollow truncated cone open at its apex and closed by a diaphragm at the opposite side, with openings in said diaphragm near the periphery thereof, means for feeding the liquid into the open side of said drum, a series of conduits 30 connected to said openings in the diaphragm for conveying the exterior portions of the separating mass away from said drum, said conduits being inclined outwardly away from said drum, and inwardly toward the axis about which said drum rotates, with 35 means for positively controlling the flow of fluid through said conduits, substantially as described. 40
6. A centrifugal separator of the character described comprising a rotary drum in the form of a hollow truncated cone open at its apex and closed by a diaphragm at the opposite side, with openings in said diaphragm near the periphery thereof, means for feeding the liquid into the open side of said drum, and a series of conduits 45 connected to said openings in the diaphragm for conveying the exterior portions of the separating mass away from said drum, with means for positively controlling the flow of fluid through said conduits, substantially as described. 50
7. A centrifugal separator of the character described comprising a rotary drum in the form of a hollow truncated cone open at its apex and closed by a diaphragm at the opposite side, with openings in said diaphragm near the periphery thereof, means for feeding the liquid into the open side of said drum, and a series of conduits 55 connected to said openings in the diaphragm for conveying the exterior portions of the separating mass away from said drum, with means for positively controlling the flow of fluid through said conduits, substantially as described. 60
8. A centrifugal separator of the character described comprising a rotary drum in the form of a hollow truncated cone open at its apex and closed by a diaphragm at the opposite side, with openings in said diaphragm near the periphery thereof, means for feeding the liquid into the open side of said drum, and a series of conduits 65 connected to said openings in the diaphragm for conveying the exterior portions of the separating mass away from said drum, with means for positively controlling the flow of fluid through said conduits, substantially as described. 70
9. A centrifugal separator of the character described comprising a rotary drum in the form of a hollow truncated cone open at its apex and closed by a diaphragm at the opposite side, with openings in said diaphragm near the periphery thereof, means for feeding the liquid into the open side of said drum, and a series of conduits 75 connected to said openings in the diaphragm for conveying the exterior portions of the separating mass away from said drum, with means for positively controlling the flow of fluid through said conduits, substantially as described. 80
10. A centrifugal separator of the character described comprising a rotary drum in the form of a hollow truncated cone open at its apex and closed by a diaphragm at the opposite side, with openings in said diaphragm near the periphery thereof, means for feeding the liquid into the open side of said drum, and a series of conduits 85 connected to said openings in the diaphragm for conveying the exterior portions of the separating mass away from said drum, with means for positively controlling the flow of fluid through said conduits, substantially as described. 90
11. A centrifugal separator of the character described comprising a rotary drum in the form of a hollow truncated cone open at its apex and closed by a diaphragm at the opposite side, with openings in said diaphragm near the periphery thereof, means for feeding the liquid into the open side of said drum, and a series of conduits 95 connected to said openings in the diaphragm for conveying the exterior portions of the separating mass away from said drum, with means for positively controlling the flow of fluid through said conduits, substantially as described. 100
12. A centrifugal separator of the character described comprising a rotary drum in the form of a hollow truncated cone open at its apex and closed by a diaphragm at the opposite side, with openings in said diaphragm near the periphery thereof, means for feeding the liquid into the open side of said drum, and a series of conduits 105 connected to said openings in the diaphragm for conveying the exterior portions of the separating mass away from said drum, with means for positively controlling the flow of fluid through said conduits, substantially as described. 110

In testimony that I claim the foregoing as my invention, I have signed my name in presence of two witnesses, this 14th day of April 1914.

GEORG JAHN.
